UNITED STATES PATENT OFFICE

105,788

DESIGN FOR A PREHEATER CABINET FOR HAIR WAVING MACHINES

Harry Cohen, New York, N. Y., assignor to Samuel Bonat & Bro., New York, N. Y., a copartnership composed of Samuel Bonat and Harry Bonat

Application May 24, 1937, Serial No. 69,525

Term of patent 7 years

To all whom it may concern:

Be it known that I, Harry Cohen, a citizen of the United States and resident of New York, in the county of New York and State of New York, have invented a new, original, and ornamental Design for a Pre-heater Cabinet for Hair Waving Machines, of which the following is a specification, reference being had to the accompanying drawing, forming a part thereof.

The figure is a view in perspective of a pre-

heater cabinet for hair waving machines, showing my new design.

The side of the cabinet not shown is substantially like the side illustrated in the drawing.

I claim:

The ornamental design for a preheater cabinet for hair waving machines, substantially as shown and described,

HARRY COHEN.
